Primary Examiner — Kevin Rudzinski*Assistant Examiner* — Kathleen Jones(74) *Attorney, Agent, or Firm* — Timothy E. Siegel Patent Law, PLLC; Timothy E. Siegel(57) **CLAIM**

The ornamental design for a rifle scope, as shown and described.

DESCRIPTION

FIG. 1 is a left side view of a rifle scope in accordance with the present invention.

FIG. 2 is a front view of the rifle scope of FIG. 1.

FIG. 3 is a rear view of the rifle scope of FIG. 1.

FIG. 4 is a right side view of the rifle scope of FIG. 1.

FIG. 5 is a top view of the rifle scope of FIG. 1; and,

FIG. 6 is a bottom view of the rifle scope of FIG. 1.

The broken lines in the figures are included for the purpose of illustrating portions of the rifle scope and form no part of the claimed design.

1 Claim, 2 Drawing Sheets(56)
